UNITED STATES PATENT OFFICE.

JOHN H. GAVIN, OF CHICAGO, ILLINOIS, ASSIGNOR TO THE L. WOLFF MANUFACTURING COMPANY, OF SAME PLACE.

DESIGN FOR A BRACKET.

SPECIFICATION forming part of Design No. 23,873, dated December 11, 1894.

Application filed November 5, 1894. Serial No. 527,977. Term of patent 14 years.

To all whom it may concern:

Be it known that I, JOHN H. GAVIN, a citizen of the United States, residing at Chicago, in the county of Cook and State of Illinois, have invented a new and original Design for a Bracket, of which the following is a specification.

The leading feature of my design consists in the general shape and outline of the bracket as a whole, comprising in connection with the two right angle arm portions of the bracket an intermediate brace portion consisting of two equal and similar semi-elliptical curves tangentially touching each other, the two extremities or limbs of each of said curves each terminating in a spiral or scroll-shape curve tangentially touching the adjacent arm of the bracket, and each of the semi-elliptical curved portions having further reverse curved branches terminating in spiral or scroll-shaped curves tangentially touching the adjacent arm of the bracket.

In the accompanying drawing, forming part of this specification, I have illustrated in perspective view a bracket showing my design.

In the drawing A A are the two right angle arm portions of the bracket; B B, the two semi-elliptical curves of the brace portion of the bracket, said curves touching each other 30 tangentially at b, and having at each extremity spiral or scroll-shaped curves B' B' tangentially touching the adjacent arms A A of the bracket. Each of these semi-elliptical curved braces B B has also a reverse curve branch 35 B², terminating in a spiral or scroll B³ tangentially touching the adjacent arm of the bracket, as illustrated in the drawing, and the curved branch B² forms a continuous ogee curve with the part B. Each of the brace 40 arms A has also an interior marginal portion a a in the plane of the curved brace portion B B, as indicated in the drawing.

I claim—

The design for a bracket herein shown and 45 described.

JOHN H. GAVIN.
